(57) CLAIM

The ornamental design for a children's bookshelf, as shown and described.

DESCRIPTION

FIG. 1 is a rear, right and top perspective view of a children's bookshelf showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left elevation view thereof, a right elevation view thereof being a mirror image of the left elevation view; and, FIG. 7 is a front, right and top perspective view thereof without the fabrics.

The broken lines depict stitches of the fabrics that form part of the claimed design.

1 Claim, 7 Drawing Sheets
